UNITED STATES PATENT OFFICE.

GUY W. FERDON, OF CRESKILL, NEW JERSEY.

COLLAPSIBLE STOVE.

1,247,806.

Specification of Letters Patent. Patented Nov. 27, 1917.

Application filed March 24, 1917. Serial No. 157,116.

To all whom it may concern:

Be it known that I, Guy W. FERDON, a citizen of the United States, residing at Creskill, county of Bergen, State of New Jersey, have invented certain new and useful Improvements in Collapsible Stoves; and I do hereby declare the following to be a full, clear, and exact description of the invention, such as will enable others skilled in the art to which it appertains to make and use the same.

My invention relates to collapsible stoves or heaters, and particularly relates to a device adapted to be used for cooking with alcohol lamps, whether the lamps be those which use solid or liquid alcohol; though the device is not restricted to the use of this particular fuel, but burners or lamps supplied with other solid, liquid, or gaseous fuel may be employed in connection with my device.

My invention particularly relates to a folding stove of the kind that can be folded into a small package and carried about in an automobile kit, by hand, or as an article of luggage, which may be instantly set up and used for picnic or other cooking.

My device relates particularly to a folding screen or heat deflector which is adaptable for use in connection with the stove shown in my Patent No. 1,199,257, dated September 26, 1916, though in the present invention it is shown and claimed as part of a stove combination wherein the stove shown is somewhat different from that of the patent aforesaid.

In the drawings:

Figure 1 is a perspective view of a stove showing my device;

Fig. 2 is a perspective view of my screen with the wings attached thereto;

Fig. 3 is a view showing a somewhat modified form;

Fig. 4 is a view showing my screen or shield in another position, where it may be used as a bench or support;

Fig. 5 shows the screen in position over a stove;

Fig. 6 shows the screen in position in the rear of a stove;

Fig. 7 shows the screen in another shape, used as a heating adjunct to the folding stove; and

Fig. 8 is a view of my stove and shield folded flat.

In the drawings, 1 represents a stove of the same general type as that of my patent, provided with my wind shield 2 having wings 3 hinged thereto at 4, and adapted to be extended forward therefrom or to be folded back flat against the shield 2. In the upper part of this shield I may provide a flange 5 adapted to fit over and hang or be hinged upon the strengthening rod or wire 6 of the hot plate of my stove, and thereby hold the screen or wind shield in position. In the said top plate I show openings 7 provided with grates 8. Each of these grates may be covered with the plate 9 so as to shut in and conserve the heat of the alcohol lamps 10, shown in outline below. These plates may cover the openings after the grates are removed, if desired, and the said openings may be covered in other ways, as by a cooking utensil, or the wind shield 1 may be laid upon said openings, or may be supported above the openings by the side wings, as shown in Fig. 5, and thus used for cooking purposes; or it may be supported in the rear, as shown in Fig. 6, where it may be used as a heating shelf, or, as shown in Fig. 7, it may be used as an additional heating space in which wood or fuel may be burned for broiling steaks, warming purposes, etc. It will be observed that the proportions of the ends of the stove and of the back and wings are such as to make this feasible.

When the wings are opened, as shown to the right in Fig. 1, these wings act as heat radiators or deflectors, and a stove with the shield thus arranged becomes a valuable heat accessory to comfort, when used, say, in a tent in cold weather. The grates, as shown, are arranged of two pieces of suitable metal, edge up, and fixed rigidly at the center. The outer ends of each of these pieces is turned flatwise, as shown, and the grate as a whole may be slipped into place in the flexible hot plate by slipping one end of one of the bars under said hot plate, as indicated at 11; bending the other end at 12 downward, thereby flexing the hot plate, and thrusting said end under the part of the opening opposite the end 11. While this flexes the hot plate, the latter, being made of iron sufficiently flexible for the purpose, serves to hold these grates in position with remarkable rigidity and security, so that very heavy vessels may be placed upon them,

or they may be subjected to a very hot fire without any loss of rigidity of support. Edges of the wings and, if desired, of the back plate of the shield are folded so as to 5 form an edge or bead, as indicated at 13. The inner edge of this bead may be lifted, as indicated at 14, and a hook or piece, as 15, may be provided to extend from such bead or lifted plates, back to engage a suitable 10 part of the upper edge of the main plate of the inner shield. This may be above or below. I may also provide a small opening, as indicated at 16, in each wing, whereby this shield may be supported as a swinging 15 shelf, say, from trees or other support, or in a tent to serve as a shelf to hold provisions safe from the attacks of rodents or other vermin.

The holes 16 may be used to connect the 20 wings 3 with the legs or shelf of the stove, if desired, thus securing the wings against outward movement when used as a shield or when used as a wood stove.

It is possible to use my shield in connection with the stove in case of exposure to a 25 strong draft, by inverting the stove and inverting the supporting shelf, the fuel, or fuel cans or lamps, are then placed upon the inverted grates at the bottom and the supporting shelf may itself become a pan or 30 rack for toasting or cooking.

I show, in Fig. 3, a modification in which the rear part of the shield 3 is shown permanently hinged to the flexible hot plate.

35 The forward extending wings are provided with brackets or supports 17 which are permanently hinged at 18 to said wings, and which may be swung up to engage clips 19 on the upper shelf or hot plate. I rivet or 40 otherwise secure to each of said wings a strap 20, and I provide a shelf 21 somewhat narrower than the hot plate, so that the air may circulate and with ends turned down to engage said strap from above, thereby holding 45 the sides rigidly together, while at the same time affording a suitable place for the support of a lamp. The edges of the shelf may be upturned to form of the shelf a pan, and for stiffening purposes.

50 It may be observed that while, as has been indicated above, my device is particularly intended for the use of alcohol lamps, particularly solid-alcohol lamps, it may serve with other fuel, as it is possible to burn a

55 newspaper on said shelf 21 gradually, and by the heat thereof to boil coffee or fry eggs in a pan over the grate openings. It is also possible to remove, in some instances, these shelves and create a fire by means of comparatively small twigs, pieces of wood, pieces of charcoal, etc.; and this fire may endure as long as desired. When arranged as shown in Fig. 7, the inclosure may be filled with larger pieces of wood, and the 60 whole arranged as a camp fire. Steaks or

chops or fish may be broiled over such a fire after it has burned to embers.

It may be observed that I have provided a device which serves to conserve the heat of my stove, and produces at the back, at least, 70 and sides, upward deflection of all the heat units of the stove. It also serves as a flame protection, preventing the flame from being acted upon by drafts and spreading to inflammable articles near by. It serves also 75 as a radiator, particularly when arranged over the stove, as shown in Fig. 5, and used in a tent. The wings of it are hinged so that the whole may be folded up and packed with the stove in a very compact manner, 80 either in the form shown in Fig. 2 or when attached permanently as a part of the stove, as in Fig. 3.

The slidingly removable grate is a very 85 convenient adjunct, as this grate may be removed when it is desired to bring cooking vessels closer to the fire; and when retained, affords opportunity of egress of flame between it and the stove, since the grate when used, raises the vessel placed thereon a fraction of an inch above the hot plate.

When using the stove with wood or other fuel without the grates, the cooking vessel is usually brought right down on top of the stove, thus closing entirely the apertures 95 from which the grates are removed and making a cooking stove of it similar to the usual coal or wood burning stove. This makes a hotter fire. When the stove is used with the fuel shelf and alcohol or similar 100 fuel, a certain amount of air is needed between the vessel and the burner; if this is not supplied, imperfect combustion ensues, with the corresponding formation of carbon monoxide, which may be dangerous in a closed 105 room. The essential parts of the swinging supports 17, are the perpendicular parts which are in effect pintles of hinges and the horizontal parts which engage the clips 19 are, in effect, latches. The diagonals are 110 simply struts or braces and are obviously not always necessary. When these latches or supports are snapped into the clips 19, the structure is rigid, well braced, and secure. When they are swung out of the clips they 115 are turned in toward or past the shelf and the top thus released may be turned up and back.

The shield may be used, when over the stove, for toasting bread, broiling fish, or 120 even baking. When folded up it may be used to set the stove upon, thereby shielding the table or other support on which the stove may be used, from the effects of heat.

It will be noted that my grates, as arranged in the manner shown, provide for expansion and contraction without warping.

I may provide other means to attach my shield to the stove, and it will be obvious that various modifications might be made in 130

the herein described stove and in the construction, combination and arrangement of parts which could be used without departing from the spirit of my invention.

5 Having thus described my invention, what I claim and desire to secure by Letters Patent of the United States, is:

1. In a collapsible stove and in combination therewith, a heating plate provided 10 with grate openings, a heat deflecting plate adapted to be hinged upon and to close the back of the stove when the latter is set up, wings hinged to said heat deflecting plate, adapted to close the ends of the stove when 15 set up, said heat deflecting plates and wings adapted when the stove is collapsed, to fold together with the stove.

2. In a collapsible stove wider than high and in combination therewith, a heating 20 plate, a heat deflecting plate having detachable connections with said heating plate and adapted to close the back of the stove, and wings secured to said deflecting plate adapted to the ends of the stove whereby it may 25 be supported above the stove flatwise when removed from the heating plate, or may be supported vertically removed from the stove, to form an additional heating space.

3. In a collapsible stove and in combination therewith, a hot plate having openings 30 therein, grates adapted to be fixed in said openings, a rear plate hinged to said top plate, side plates hinged to said rear plate, a shelf whereby fuel may be supported in 35 proper relation to said hot plate openings, folding supporting means for said top plate, and means, whereby said shelf may be connected to said supporting means, to hold the latter rigid.

4. In a collapsible stove, and in combination therewith, a hot plate, collapsible means for supporting it, a rear plate hinged to said hot plate, end plates or wings hinged to 40 said rear plate, said rear plate and wings 45 being detachable as a whole from the said hot plate, and being of such dimensions as to adapt them to various positions with relation to the stove when detached so as to form a shelf over or in rear of the stove for 50 warming purposes.

5. A stove, a hot plate therefor, a folding wind shield in combination with said stove, said shield consisting of a back and wings, and a stove shelf for said stove said wings 55 provided with means whereby the wings may be supported against the shelf and plate

in wind shielding position, by means engaging the shelf.

6. In a combination stove and wind shield, a hot plate, legs hinged to the under side 60 of said plate and adapted to be folded against said plate, means for keeping said legs in open position said means adapted to fold against said legs, means when the device is in use for supporting the heating 65 device in proper relation to said hot plate, and means whereby the wind shield may be hinged to the stove and held against the hot plate, to shield the burners, when the 70 stove is in operation.

7. In a combination stove and wind shield, a hot-plate, legs hinged thereto, means for keeping said legs extended, a heating shelf below the hot plate, a winged wind shield hinged upon the hot plate and means whereby the wings may be secured to the shelf 75 and thus to each other.

8. In a collapsible stove, a hot plate, a wind screen adapted to be connected to said hot plate, means for supporting said hot 80 plate, a stove shelf for said stove detachably connectible to said supporting means, and wings attached to said screen, said wings adapted to extend forward past the shelf or to form supports for said screen, when 85 the latter is placed away from or over the stove.

9. A collapsible stove, having a hot plate at the top thereof, a flanged stove supporting shelf adapted to be detachably held in 90 proper relation to said plate and a wind shield for said stove extending the height of the stove and attachable to said stove, the stove being invertible so that heating agents may rest upon the hot plate, while objects 95 to be heated are supported on the shelf, the wind shield being adapted to be attached to and to inclose the stove when in this position to protect the fire from strong draft.

10. In a portable stove, a hot plate, supports hinged to opposite edges of said hot plate, a lamp shelf narrower than the hot plate arranged below the hot plate, means, whereby said lamp shelf and supports may be connected so as to hold each other rigid 100 and a wind shield for said stove arranged to be supported by said hot plate and connected to said supports.

In testimony whereof, I affix my signature.

GUY W. FERDON.
